GAP CLOSURE ATTACHMENT FOR KNITTING MACHINES

Filed June 5, 1924

Inventor
Edward Jackson,

By
W. G. S. Stewart

Attorneys

UNITED STATES PATENT OFFICE.

EDWARD JACKSON, OF READING, PENNSYLVANIA, ASSIGNOR TO THE NOLDE AND HORST COMPANY, OF READING, PENNSYLVANIA, A CORPORATION OF PENNSYLVANIA.

GAP-CLOSURE ATTACHMENT FOR KNITTING MACHINES.

Application filed June 5, 1924. Serial No. 717,935.

To all whom it may concern:

Be it known that I, EDWARD JACKSON, a citizen of the United States, residing at Reading, in the county of Berks and State of Pennsylvania, have invented certain new and useful Improvements in Gap-Closure Attachments for Knitting Machines, of which the following is a specification.

My invention relates particularly to circular knitting machines employing a latch guard ring having a gap for securing the movable yarn-guide members ordinarily employed as more fully set forth in Robinson Patent No. 1,357,252 of November second, 1920; and it consists of an improved straight bar closure member with independently controlled means to determinedly project or retract the same across said gap in a plane substantially tangential to said guard ring. The invention is fully described in connection with the accompanying drawing, and the novel features particularly pointed out in the subjoined claims.

Fig. 1 is a plan view showing my invention applied to a latch ring and indicating operating means adapted to be carried on the table portion of the machine; only one of the series of cooperating yarn guides employed being shown.

Fig. 2 is a cross sectional view taken on the line 2—2 of Fig. 1, but showing the closure bar moved to gap closing position, its retracted position being indicated in dotted lines.

Fig. 3 is a partial sectional view on the line 3—3 of Fig. 1.

As shown in the drawings A represents a latch ring and C the gap formed therein between parallel arms C¹ and C², the latter carrying a pivot pin C³ for a series of automatically operated thread guide fingers B, one only of the latter being shown. Each guide B is operated by its own pattern controlled push rod F and the parts thus referred to are of known structure as more fully set forth in said Robinson patent aforesaid, which also fully describes the necessity and function of a closure for said gap C to prevent "flirting" of the needle latches.

In the present improvements, shown in preferred manner in the drawing, I employ

a gap closure member H formed from a straight round bar or wire of proper diameter cut to proper length. This bar is carried in a bearing bracket I secured to the ring A as shown and is adapted to be moved axially therein through ring aperture J alined with said bracket carried bar so as to transversely cross said gap C at a point 55 substantially tangential to the open ring A, where it will act in well known manner to prevent unintended swinging of the latches.

The bracket I as shown fixedly carries a guide rod K extended therefrom in parallel relation to said bar H, and the latter is provided with a fixed end collar L slidably engaging said guide rod K so as to support and insure free axial movement of bar H at all times. A spring M strung on said bar 60 H between bracket I and collar L normally retains said bar in retracted position away from gap C, but free to move across the latter when bar J is moved axially against the tension of said spring M.

The bar J may be moved in any convenient manner, but in the drawings I have shown a simple means operated from the usual pattern mechanism to determinedly actuate the same. This consists of a radially swinging arm N, pivotally carried in a bearing or bearings O secured to the machine frame P, a crank extension R of the bearing engaged portion pivotally engaging a push rod S. The rod S may be actuated 75 as desired from the usual pattern drum, not shown, but commonly employed, to swing arm N into contact with collar L to move bar J against the tension of its spring M so as to project said bar across gap C when required. Spring M will retract bar J when pattern mechanism frees arm N.

The specific structure above set forth may readily be modified, the essential features of the present invention comprising the simple straight bar J moved axially to close the gap as more specifically set forth in the claims.

What I claim is:

1. In a knitting machine the combination 100 with a plurality of pivotally operated thread-guide members and a latch ring having a thread-guide gap, of a gap closing member comprising a straight bar movable

across said gap in a plane substantially tangential to said ring, and means for determinedly moving and retracting said bar.

2. In a knitting machine the combination with a plurality of pivotally operated thread-guide members and a latch ring having a thread-guide gap, of a gap closing member comprising a straight bar movable across said gap in a plane substantially tangential to said ring, means to normally retract said bar, and means to determinedly project the same across said gap.

3. In a knitting machine the combination with a plurality of pivotally operated thread-guide members and a latch ring having a thread-guide gap, of a gap closing member comprising a straight bar normally projecting outside said ring, and means for

determinedly moving the same axially to cross said gap in a plane substantially tangential to said ring.

4. In a knitting machine the combination with a plurality of pivotally operated thread-guide members and a latch ring having a thread-guide gap, of a gap closing member comprising a straight bar, a bearing therefor outside said ring, a parallel guide rod, a spring on said bar between said collar and bearing, a ring aperture extending to said gap aligned with said bearing, and means for determinedly moving said bar axially against said spring tension to project the same across said gap in a plane substantially tangential to said ring.

In testimony whereof I affix my signature.

EDWARD JACKSON.
